UNITED STATES PATENT OFFICE.

GEORGE W. BOOZER, OF SAN ANTONIO, TEXAS.

WRENCH.

SPECIFICATION forming part of Letters Patent No. 703,636, dated July 1, 1902.

Application filed November 11, 1901. Serial No. 81,896. (No model.)

To all whom it may concern:

Be it known that I, GEORGE W. BOOZER, a citizen of the United States, residing at San Antonio, in the county of Bexar and State 5 of Texas, have invented certain new and useful Improvements in Wrenches; and I do hereby declare the following to be a full, clear, and exact description of the invention, such as will enable others skilled in the art to which 10 it appertains to make and use the same.

My invention relates to improvements in wrenches; and it consists in the improved means for operating the movable jaw thereof.

In the accompanying drawings, illustrating 15 my invention, and in which like parts are designated by the same letters of reference in the several views, Figure 1 is a side elevation of my improved wrench, the handle thereof being broken away and showing the movable jaw in section. Fig. 2 is a perspective view of the lever for operating the clutch-plate; and Fig. 3 is a side elevation of the 20 fixed jaw, showing the milled surface on the inner side of the shank.

25 *a* represents the side of the shank of the wrench provided with the usual handle, (not shown,) and *b* is the fixed jaw of the same.

c represents a movable jaw, which is hollowed out or recessed, as at *d*, and provided 30 with the connecting webs or ears *e f*, engaging the outer surface of the shank. The recess *d* is enlarged at its upper end, as at *g*, and extends into the projecting portion which forms the gripping-surface of the movable 35 jaw. In this enlarged portion *g* of the recess is fitted the movable clutch-plate *h*, provided with the angular and milled surface *i*, adapted to engage with the milled surface *j* on the inside of the shank of the wrench. The 40 plate *h* being loosely mounted in the enlarged portion of the recess is free to move upwardly or downwardly for a certain distance, but on account of the shape of the recess the outer or rounded edge of the plate is capable only 45 of a comparatively limited movement. This clutch or locking-plate *h* is also provided on its underneath side with the curved lug or projection *k*.

l represents a lever preferably provided at 50 one end with the curved finger *m* to facilitate the manipulation of the lever and movable jaw. The lever *l* at its other end is pro-

vided with the curved shoulder *n*, engaging the curved lug *k* for operating the locking-plate *h*. The lever *l* is also provided with 55 the lug *o*, adapted to engage in a shallow groove *p*, disposed longitudinally of the shank of the wrench, and acts as the fulcrum of the lever. Lugs *q* are formed on the sides of the lever and engage a coiled spring *r*, surrounding the lever and supported at its other end by the base of the movable jaw. Although I have shown a coiled spring surrounding the lever it will be obvious that any other suitable method of retaining the lever and locking-plate in the proper position relative to each other may be employed, if desired. It will be understood that the base of the movable jaw is suitably slotted, as at *s*, to allow of the passage of the lever *l* therethrough. 70

The operation of the device is as follows: When the wrench is to be disengaged from the nut or bolt operated upon, the operator presses inwardly on the curved finger or handle of the lever, which, turning on its fulcrum *o*, presses outwardly and downwardly on the curved lug *k* of the locking-plate, releases the same from engagement with the milled surface of the shank, and allows the jaw to be moved freely in either direction on the 75 shank. The spring *r* being compressed during the inward and slightly-downward movement of the lever will, upon the lever being released, force the locking-plate or clutch back again into engagement with the milled 80 surface of the shank, thus preventing further downward movement of the movable jaw. While the lever is in the position shown in Fig. 1 it is therefore obvious that any attempt to move the movable jaw away from 85 the fixed jaw will make the locking-plate bind tighter against the shank, to be released only by operating the lever. It is also obvious that the movable jaw can at all times be moved toward the fixed jaw, independent of 90 the operation of the lever.

While I have described my invention in detail as above, it is evident that various modifications might be made without departing from the spirit of my invention; but 95

What I claim, and desire to secure by Letters Patent of the United States, is—

1. In a wrench, the combination with the fixed jaw and shank, of a hollow movable jaw

- having an enlarged recess in the upper portion thereof extending into the projecting lip of said movable jaw, a locking-plate loosely mounted in said movable jaw engaging at 5 one end said enlarged recess and at its other end said shank, and a lever engaging said locking-plate and movable transversely of said movable jaw for disengaging said locking-plate and shank.
- 10 2. In a wrench, the combination with the fixed jaw and milled shank, of a hollow movable jaw provided with an enlarged recess in the upper portion thereof, a locking-plate, loosely carried in said hollow movable jaw, engaging at one end the wall of said enlarged recess and at its other end provided with a milled angular surface engaging said milled shank, and a lever engaging said locking-plate and movable transversely of said hollow 15 jaw for disengaging said locking-plate and shank.
- 15 3. In a wrench, the combination with the shank and fixed and movable jaws, of a locking-plate carried by said movable jaw and engaging said shank, a curved lug formed on 20 said locking-plate, and a spring-controlled lever provided with a curved shoulder engaging said curved lug and movable transversely of said movable jaw for releasing said locking-plate.
- 25 4. In a wrench, the combination with the 20
- fixed jaw and shank, a shallow groove disposed longitudinally of said shank, a hollow movable jaw provided with an enlarged recess, a locking-plate mounted in said enlarged recess and engaging said shank, a lever engaging said locking-plate and a lug on said lever engaging said shallow groove and adapted to act as the fulcrum of said lever when the lever is moved transversely of the 35 hollow jaw for releasing the locking-plate.
5. In a wrench the combination with the fixed jaw and milled shank, of a hollow jaw provided with an enlarged recess at the upper portion thereof, a locking-plate loosely 40 mounted in said enlarged recess and engaging said milled shank, a curved lug formed on said locking-plate, a lever carried by said movable jaw, provided at one end with a curved finger or handle portion and at its 45 other end with a curved shoulder adapted to engage said curved lug on the locking-plate, lugs formed transversely of said lever, and a spring engaging said transverse lugs and said movable jaw for retaining said lever in position.
- 50 In testimony whereof I affix my signature in presence of two witnesses.
